UNITED STATES PATENT OFFICE.

HARVEY CORTLAND AND JOHN T. HUME, OF PITTSBURG, PENNSYLVANIA;
SAID HUME ASSIGNOR TO SAID CORTLAND.

AUTOMATIC FIRE-ALARM.

SPECIFICATION forming part of Letters Patent No. 677,954, dated July 9, 1901.

Application filed December 30, 1899. Serial No. 742,061. (No model.)

To all whom it may concern:

Be it known that we, HARVEY CORTLAND and JOHN T. HUME, citizens of the United States, and residents of Pittsburg, in the 5 county of Allegheny and State of Pennsylvania, have invented an Improvement in Automatic Fire-Alarms, of which the following is a specification.

Our invention relates to an automatic fire-alarm, and has for one object to provide a combined controller and annunciator, thereby dispensing with two separate electrical indicator mechanisms.

A further object is to provide for mechanically and simultaneously setting the controller and indicator.

A further object is to mechanically connect the indicator with the controller to insure a positive movement of the indicator.

20 A further object is to provide a controller for an automatic fire-alarm system in which the indicator is mechanically moved and so arranged that the operation of the system is entirely independent of the failure or non-25 failure of such indicator device.

30 A further object is to provide a controller for an automatic fire-alarm system in which the breaking of a wire will immediately give a trouble-alarm and the controller automatically change the connections in such manner that in the event of a fire a fire-alarm may be sent in before repairs are made to the wire.

35 In the drawings, Figure 1 represents a side elevation, partly in section. Fig. 2 is a section taken on lines X X, Fig. 1. Fig. 3 is a plan view showing the indicator. Fig. 4 is a detail view showing the escapement. Fig. 5 is a detail showing the resetting mechanism. 40 Fig. 6 is a detail showing the gear for limiting the rotation of the main shaft.

1 designates the base of the instrument; 2, a stud extending from the base.

3 is an annular insulating-ring.

45 4 is a standard fixed to the base and which supports the stop-lever 5 and armature 6.

To the annular ring 3 is secured a plurality of brushes 7. On stud 2 is a sleeve 8, loosely journaled thereon, to which is secured 50 the disk 9, having a plurality of insulated

contact-plates 10 attached thereto. In disk 9 is a notch 9', engaging with which is a finger 10' for the purpose of moving said disk. The disk 9 is provided with a recess into which projects finger 62.

55 11 is an electromagnet, a portion thereof being omitted to better disclose the mechanism in rear thereof.

Loosely journaled upon the stud 2 is the pinion 12, to which is secured the radial arm 60 13, said arm having an insulating-piece 14 secured to its outer end, the purpose of this arm being to force brushes 7 outwardly from contact with plates 10 when revolved.

15 designates a segmental gear secured to 65

shaft 16 and adapted to mesh with pinion 12, thereby rotating arm 13. The lower end of main shaft 17 is stepped in the upper end of stud 2 and passes through plates 18 and 19.

Journalized in plate 19 is a squared winding-70

shaft 20, having attached thereto gear 21, meshing with gear 22, said gear being secured to disk 23, the gear and disk being free to revolve upon the main shaft. Upon the lower

face of disk 23 is the stud 24, to which is attached the outer end of the mainspring 25, the inner end being secured to the main shaft.

On stud 26, secured to the disk 23, is a planetary gear 27, meshing with the pinion 28, secured upon the main shaft, gear 27 having 80

a portion of its periphery uncut, as at 29, whereby the rotation of the main shaft is limited.

Fastened to plate 19 is a pawl 30, adapted to engage with the teeth of gear 21. Upon the periphery of disk 23 is formed one 85

or more gear-teeth 31, meshing with the pinion 33, loosely mounted upon a stud secured to plate 19, said pinion meshing with a gear 32, secured to shaft 16, the purpose of which

is to rotate shaft 16 when disk 23 is rotated 90 in the act of winding the spring, thereby resetting an indicator-pointer 34 and the radial arm 13. Spring 25 is housed between plates 35 and 36. Secured to shaft 17 is an inter-

mittent gear 37, meshing with the segmental 95 gear 38, secured to shaft 16. Secured upon shaft 17 is a gear 39, meshing with pinion 40, loosely mounted upon a stud upon plate 18. Secured to pinion 40 is a gear 41, meshing with a pinion 42, loosely mounted upon 100

shaft 17. Secured to pinion 42 is an escapement-wheel 43, with which the escapement-lever 44, having an adjustable weight 45, engages, the lever 44 being pivotally mounted upon a stud affixed to plate 18, the object of the adjustable weight being to regulate the speed of the train of gearing. To gear 43 are secured projections 46 and 47, adapted to make engagement with the stop-lever 5. Secured to shaft 17 is a disk 48, having a peripheral notch 49, into which stop-lever 5 may be forced by the spring 50. Secured to the top of plate 19 is a stud 51, upon which is loosely journaled a sleeve 52, upon which is secured a disk 53, and beneath disk 53 is a pinion 54, frictionally held upon sleeve 52. Secured to disk 53 is the indicator-pointer 34, adapted to indicate the box from which the signal is being transmitted. To the upper end of shaft 16 is secured a segmental gear 55, adapted to mesh with pinion 54, the object of which is to move the indicator-pointer 34 by means of pinion 54, sleeve 52, and disk 53. The object of frictionally securing pinion 54 to sleeve 52 is to allow said pinion to continue its revolution after disk 53 and its attached pointer has been stopped, as will be hereinafter described. Disk 53 is formed with a plurality of peripheral notches 56, adapted to be engaged with lever 57, said lever being held out of engagement by electromagnet 58, spring 59 forcing said lever into the peripheral notches upon the demagnetization of magnet 58, it being demagnetized when the radial arm 13 forces the brushes out of contact with the plates 10, as will be further described.

The switching mechanism is such that the wiring of a building is normally connected in series with magnet 11. Should a wire be cut or broken, magnet 11 is demagnetized. Spring 50 forces lever 5, with its attached armature, out of contact with stop 46, releasing the mechanism. Upon the rotation of shaft 17 the intermittent gear 37 engages with segmental gear 38, thus partially rotating shaft 16, segmental gears 15 and 55, and by means of finger 10' moving disk 9 and its attached contact-plates, thereby changing the wiring, passing finger 62 in rear of lever 5, sending in a trouble-alarm by means of notched break-wheel 60 and insulated brush 61. The mechanism is stopped upon one revolution of the main shaft by means of spring 50 forcing lever 5 into notch 49 in disk 48, thereby bringing the lever into contact with stop-piece 47. Segmental gears 15 and 55 are now in position to engage pinions 12 and 54, respectively, upon the next partial revolution of shaft 16. In the event of a fire occurring (it being understood that the system is wired by a series wire and an annunciator-wire for each floor or room, having thermostats or manual circuit-closing devices connected in multiple therewith) magnet 11 is energized, attracting armature 6 and attached lever 5, withdrawing said lever from notch 49 and engagement

with stop 47, the outward movement of said lever being limited by finger 62, releasing the mechanism by allowing lever 5 to pass between stops 46 and 47. On the further rotation of shaft 17 pinion 37 moves shaft 16 by means of segmental gear 38, gear 15 engages pinion 12, and gear 55 engages pinion 54, thereby moving radial arm 13, disk 53, and pointer 34 in unison. When arm 13 forces the brushes corresponding to the floor or room in which the fire occurs from the contact-plates, it opens the circuit, thus demagnetizing magnets 11 and 58, thereby releasing lever 57, said lever being forced into engagement with one of the notches 56 in disk 53, thus stopping the further rotation of disk 53 and pointer 34. Shaft 16 continues its rotation until segmental gear 38 passes out of engagement with pinion 37, pinion 54 slipping on sleeve 52 and radial arm 13 being moved to its stopped position and out of engagement with the brushes, the rotation of shaft 17 being continued until stopped by the uncut portion 29 of gear 27 engaging with pinion 28, the fire-alarm being transmitted by means of break-wheel 60 and brushes 61, properly connected, after which the mechanism may be reset in the act of winding in the manner clearly evident from the foregoing description. Upon the rotation of disk 23 teeth 31 engage with intermediate gear 33, which by means of gear 32 rotates shaft 16, segmental gears 15 38 55, radial arm 13, disk 53, and pointer 34, and by means of finger 10' returns disk 9 and attached contact-plates to its normal position, withdrawing finger 62 from engagement with lever 5, thereby allowing energized magnet 11 to bring lever 5 into engagement with stop 46, thus holding the mechanism in readiness for another alarm.

What we claim is—

1. In an automatic fire-alarm, a controller having a plurality of brushes, contact-plates normally in contact with the brushes, an arm revolvably pivoted to travel in the path of the brushes and means for actuating this arm to urge the brushes out of contact.
2. In an automatic fire-alarm, a shaft having mounted thereon a plurality of segmental gears, a pointer actuated by one of the segmental gears, an arm actuated by another of the segmental gears, the shaft being revolved by the remaining segmental gear, a switch-plate having insulated contacts thereon and a peripheral notch therein, fixed brushes engaging said contacts and a finger upon the shaft, adapted to engage said notch and thereby move said plate.
3. In an automatic fire-alarm, a combined controller and indicator, the controller having a plurality of brushes, contact-plates normally in contact with the brushes, an arm adapted to revolve in the path of the brushes and means for actuating the said arm to force the brushes out of contact, of a shaft having a plurality of segmental gears and finger mounted thereon, a pointer actuated

by one of the said gears, another of the gears adapted to actuate said arm, a second shaft being revolved by the remaining gear and a switch-plate upon the shaft supporting said 5 contact-plates and having a peripherical notch adapted to be engaged by said finger, substantially as shown and described.

In testimony whereof we have subscribed our names in the presence of two witnesses.

HARVEY CORTLAND.

JOHN T. HUME.
